UNITED STATES PATENT OFFICE.

CHARLES S. DIKEMAN, OF TORRINGTON, CONNECTICUT.

DESIGN FOR A SPROCKET WHEEL OR GEAR.

SPECIFICATION forming part of Design No. 29,450, dated October 4, 1898.

Application filed August 28, 1898. Serial No. 689,356. Term of patent 14 years.

To all whom it may concern:

Be it known that I, CHARLES S. DIKEMAN, of Torrington, county of Litchfield, and State of Connecticut, have invented and produced a certain new and original Design for a Sprocket Wheel or Gear, of which the following is a full, clear, and exact description, reference being had to the accompanying drawings, forming a part thereof.

In the drawings, Figure 1 is a view in perspective, and Fig. 2 is a view in section.

The leading feature of my design consists in the sprocket wheel or gear having the peculiar pattern or configuration of open-work which occupies the interior of the sprocket between the rim and hub portions, as illustrated in the drawings.

Six spokes or arms 1 radiate from the hub 2 and merge into the rim 3 at their outer ends. The spokes or arms 1 at a point between their ends diverge so as to form circular portions 4. V-shaped braces or webs 5 are disposed between the spokes and the rim and are

merged into said spokes at the circular portion thereof and into the rim equidistant between the spokes. Between each two spokes and the V-shaped brace a figure pointed at one end, gradually widening, and then again diminishing and again widening and having a rounded end is made. Between the braces, 25 spokes, and rim a curvilinear figure having no parallel sides is formed. The hub 2 of the wheel is made with an elongated opening 6, having parallel sides and rounded ends. Projections or teeth 7 are disposed on the rim 35 around the periphery of the wheel or gear. A gracefully-curved and attractive configuration is thus produced.

I claim as my invention—

The design for a sprocket wheel or gear substantially as shown and described.

CHARLES S. DIKEMAN.
